UNITED STATES PATENT OFFICE.

HENRY E. BECK, OF DENNISON, OHIO, ASSIGNOR TO THE DENNISON FOUNDRY AND MACHINE COMPANY, OF DENNISON, OHIO.

FIRE-POT FOR FURNACES.

1,209,106.

Specification of Letters Patent. Patented Dec. 19, 1916.

Application filed May 25, 1916. Serial No. 99,880.

To all whom it may concern:

Be it known that I, HENRY E. BECK, a citizen of the United States, residing at Dennison, in the county of Tuscarawas and 5 State of Ohio, have invented certain new and useful Improvements in Fire-Pots for Furnaces, of which the following is a specification.

This invention relates to furnace fire pots 10 and has as one of its objects to provide a fire pot so constructed as to provide for supply of heated air above the level of the burning fuel by providing air passages or ducts within the wall of the fire pot opening at 15 their lower ends into the ash pit and at their upper ends opening through the inner surface of the said wall near the top thereof. While advantageous results are secured by providing the wall of a fire pot with such 20 passages, nevertheless, the presence of the passages in the wall is liable to result in unequal expansion of the wall and unless some means is provided to prevent, the wall is liable to fracture because of such unequal 25 expansion thereof.

Therefore, the invention aims also to provide means for resisting the strains incident to unequal expansion of the wall and for this purpose the invention contemplates the 30 provision of integral outwardly extending flanges entirely surrounding the wall, these flanges serving the further purpose of conducting heat from the solid portions of the wall to the hollow portions thereof, thereby 35 not only resulting in all portions of the wall being substantially equally heated, but also serving to increase the area of the radiating surface of the fire pot.

In the accompanying drawings:—Figure 40 1 is a top plan view of a fire pot constructed in accordance with the present invention, a portion being shown in section; Fig. 2 is a vertical sectional view therethrough on the line 2—2 of Fig. 1.

The fire pot embodying the present invention is of the usual hollow frusto-conical form and the wall thereof is indicated in general by the numeral 1. At suitable intervals in its circumference the wall 1 is 45 formed with air passages 2 which open at their lower ends, as at 3, through the lower edge of the said wall and which at their upper ends communicate with the interior of the fire pot through slots 4 formed in the 50 inner surface of the wall 1, the said slots 55 4 being located relatively close to the upper edge of the said wall. At this point it will be understood that when the fire pot is properly installed within the furnace, the passages will communicate at their lower ends 60 with the interior of the ash pit of the furnace and upward draft will be created through these passages as the fuel is consumed, the air being heated and being discharged through the slots 4 into the fire pot 65 above the burning fuel.

The air passing upwardly through the 70 passages 2 will tend to cool the wall of the fire pot in the vicinity of the passages and thus the said wall will be subjected to unequal degrees of expansion at various points in its circumference and this would be liable to result in fracture of the wall of the fire pot if it were not for the provision of the means which will now be described.

In the drawing, the numeral 5 indicates a series of flanges each of which extends continuously circumferentially of the wall 1 and these flanges are integral with the said wall and are suitably spaced one above another throughout the height of the fire pot, the flanges occupying substantially horizontal planes and being preferably gradually thinned in the direction of their outer edges. Also it will be noted that the flanges are unbroken, or in other words, integral throughout their entire extent. The flanges, in the present structure, serve three purposes. In the first place they serve to increase the area 80 of the radiating surface of the fire pot and thereby provide for more thorough heating of the surrounding air; in the second place they cause a more even distribution 85 of heat throughout the area of the wall of the fire pot, thereby tending to equalize 90 the expansion of the said wall throughout all of its portions; and, in the third place they serve to bind the wall of the fire pot and thereby prevent fracture thereof due to 95 uneven expansion of the wall in the vicinity 100 of the solid and hollow portions thereof.

Having thus described the invention, what is claimed as new is:

1. A furnace fire pot provided in its wall with a plurality of air passages opening 105 through the lower edge of the said wall and at their upper ends opening through the inner face of the wall, and continuous cir-

circumscribing flanges surrounding the said wall and spaced one above another throughout the height of the said wall.

2. A furnace fire pot having a wall integral throughout and provided in its said wall with a plurality of air passages extending upwardly therethrough and arranged in a series extending around the said wall, the passages at their lower ends opening

through the lower edge of the wall and at 10 their upper ends terminating short of the upper edge of the said wall and opening through the inner surface of the wall, the said wall being provided with a plurality of integral circumscribing reinforcing flanges 15 unbroken throughout their extent.

In testimony whereof I affix my signature.
HENRY E. BECK. [L.S.]
